UNITED STATES PATENT OFFICE

CLARENCE E. LOMAX, OF OAK PARK, AND LEONARD L. RUGGLES, OF WHEATON, ILLINOIS, ASSIGNORS TO RESERVE HOLDING COMPANY, OF KANSAS CITY, MISSOURI, A CORPORATION OF DELAWARE

TELEPHONE SYSTEM

Application filed September 9, 1927. Serial No. 218,391.

The present invention relates to automatic telephone systems in general but is concerned more particularly with methods of establishing so-called "two-number" toll connections between two automatic telephone systems located in adjacent cities.

The inter city toll lines terminate in a suburban automatic exchange which is part of the automatic system serving the first large city. Due to the location of this suburban exchange, which is approximately halfway between the two cities, calls to subscribers' lines terminating in the suburban exchange from either city and calls from such subscribers' lines to the subscribers in either city are not assessed a toll charge and are, therefore, completed without the aid of a toll operator.

The subscribers having lines terminating in the automatic exchanges in both cities are, however, charged a nominal toll fee for intercity calls and, therefore, such intercity calls are intercepted by a toll recording operator in order to make a record of these calls. Subscribers in the first city as well as the subscribers in the suburban exchange prefix the digit "0" before dialing the regular directory telephone number of the desired subscriber in the second city. The subscribers in the second city also prefix the digit "0" before dialing the regular directory telephone number of the desired subscriber in the first line city or suburban exchange.

The main object of the invention is to improve the methods of completing intercity toll calls between subscribers in the two cities by reducing the duties to be performed by the toll recording operator in intercity toll calls.

A feature of this invention consists in the provision of a register sender which is taken into use only on intercity calls and which registers the digits of the called number, retransmits a certain number of the digits and stops, signals the toll recording operator, and is then restarted by the operator in order to retransmit the remaining digit or digits of the called number.

According to another feature of the invention, calls originating in the suburban exchange for the second city are routed over the same outgoing trunks which are accessible to

the register senders for extending intercity connections. As suburban subscribers are not charged for calls to the second city, it is not necessary in a suburban to the second city call to include a register sender in the connection and, therefore, the suburban subscribers have direct access by way of first selectors to the same outgoing trunks to the second city as the register senders. By this trunking arrangement the subscribers in one automatic district are divided into two classes and the subscribers in one class (suburban subscribers) are given free service while the subscribers in the other class (city subscribers) are assessed a toll charge although both classes of subscribers dial the same call number and use a common group of trunks.

Another feature of the invention relates to a discriminating register sender which either signals the toll recording operator or not depending upon whether the calling subscriber in the second city is calling a subscriber in the first city or a subscriber in the suburban exchange.

According to a further feature, the number of digits untransmitted by the register sender at the time the operator is signalled can be varied by suitable cross-connections between terminals provided for such a purpose.

Referring now to the drawings comprising Figs. 1-3, inclusive, Fig. 1, shows diagrammatically part of the inter-exchange trunking between a main exchange in the first city, denoted herein as the Muncie exchange, the suburban or Midway exchange, which is in reality part of the automatic system of the first city although located approximately half-way between the two cities, and a main exchange of the second city, known as South exchange. Figs. 2-3, inclusive, show by means of the usual circuit diagrams a sufficient amount of apparatus in the system embodying the principles of the invention to enable the invention to be described and understood.

The drawings may now be described more in detail, reference being first had to the layout of the Muncie office, Fig. 1. The reference letter A indicates a subscriber station

of the usual automatic type. At the Muncie office, with which the substation A is associated, the subscriber's line terminates in the usual line or trunk selecting switch LS. A

5 number of these lineswitches have common access to a group of first selectors such as selector DS.

The first selectors, otherwise known as district selectors, are used to select trunk lines 10 to different districts in the system. The district selector DS is indicated as having access to four telephone districts accessible from the sixth, seventh, eighth, and ninth levels. The outgoing trunk lines terminating 15 in the tenth level of the district selectors are used by the subscribers in the Muncie office for completing telephone connections to the subscribers in the second city. According to the usual practice, if there are more 20 than ten trunks in a group extending to any one district, secondary lineswitches may be used in order to give all of the selector switches common access to all of the trunks. This latter arrangement, however, is not indicated 25 in the drawing. As the Muncie office is in the sixth district, the trunk lines extending from the sixth level of the district selector DS terminate in second selectors such as indicated at OS. The second selectors, otherwise 30 known as office selectors, are used to select trunk lines to the different offices in the same telephone district. The second, third, and fourth levels of the office selectors such as OS give access to groups of outgoing trunks 35 extending to different offices in the sixth telephone district of the system. The outgoing trunks for the Midway office, which is in the sixth telephone district also, extend from the fifth level of the office selectors, as indicated 40 in the drawing. As the Muncie office is in the sixth district and is the sixth office in such district the sixth level of the office selectors are used for completing calls to the Muncie subscribers. As indicated in the 45 drawings the trunks extending from the sixth level terminate in thousands selectors such as indicated at TS. Following the usual practice, the thousands selectors have access to ten groups of hundreds selectors such 50 as selector HS, and the hundreds selectors in each group have access to ten groups of connectors such as connectors C. The connectors, of course, will have direct access to the subscribers' lines.

55 Incoming calls from the Midway office and incoming calls from the second city are handled by means of incoming selectors which have their banks multiplied with the thousands selectors. One of these incoming 60 trunks is shown as terminating in the incoming selector IS which has its banks multiplied with the banks of the thousands selectors TS. Incoming calls from other telephone districts use incoming second selectors 65 which have their bank contacts connected in

multiple with the bank contacts of the office selectors such as selector OS. This arrangement, however, is not indicated on the drawings.

The layout of the Midway office follows 70 the same general plan as has been explained in connection with the Muncie office, except for certain changes which will be described more fully hereinafter. In the Midway office, the reference letter A' indicates a subscriber's 75 station of the usual automatic type and the switches LS', DS', OS', TS', IS', HS', and C' are similar to the switches shown in the Muncie office and have in general the same 80 trunking arrangement.

The outgoing trunk lines from the tenth level of the district selectors such as DS' extend to repeaters such as REP and terminate in incoming district selectors such as IDS in the South office which office is located in the 85 seventh district of the second city network. This group of trunk lines is for use by the subscribers in the first city as well as subscribers in the Midway office for calling any subscriber in the second city.

The previously mentioned outgoing trunk lines from the Muncie exchange for calling subscribers in the second city terminate in trunk relay groups such as TR in the Midway office. A register sender selector, such as RSS 90 is associated with each trunk relay group for automatically selecting an idle register sender such as RS. When a call is received on the trunk relay group TR the register sender selector RSS automatically hunts for and selects an idle register such as RS. When an idle register sender is seized the trunk relay group causes an outgoing secondary lineswitch such as OLS to automatically hunt for and seize an idle trunk of the group extending from Midway to South.

Outgoing calls from the Midway office to the Muncie office are completed over the outgoing trunks extending from the sixth level of the office selectors. One such trunk line is indicated as extending from the sixth level of the office selector OS' to the repeater REP. Outgoing calls to other offices in the sixth district are completed over trunk lines coming from the second, third, and fourth levels 100 of the office selectors while calls to local subscribers are completed via the fifth level from which trunks extend to thousands selectors such as indicated at TS'. Outgoing calls to other districts are completed over the seventh, eighth, and ninth levels accessible to the district selectors such as DS'.

Since the Muncie office is in the same district as the Midway office the incoming trunks from the Muncie office terminate in incoming selectors which have their banks multiplied with the thousands selectors in the Midway office. One such trunk is indicated in the drawings as terminating in the incoming se- 110

lector IS' which has its banks multiplied with the banks of the thousands selectors TS'.

Incoming trunks from the second city terminate in trunk relay groups such as indicated at TR'. The trunks relay group TR' is similar to the trunk relay group TR and has a register sender selector such as RSS' associated therewith which is similar to the register sender selector RSS. The register sender selectors such as RSS' have access to a group of register senders one of which is indicated at RS'. Each trunk relay group such as TR and TR' have conductors leading to a toll recording operator's position. Associated with each trunk relay group TR' there is provided a combined district and office selector such as indicated at DOS. Each of the office selectors DOS must have access to groups of trunk lines extending to the seventh, eighth, and ninth districts and must have access also to groups of trunk lines extending to the various offices in the sixth district. The seventh, eighth, and ninth levels of the selectors DOS are connected in multiple with the seventh, eighth, and ninth levels of the district selectors in the Midway office by means of which such combination district and office selectors may extend connections toward subscribers' lines in the seventh, eighth, and ninth districts. The second, third, fourth, fifth, and sixth levels of the selectors DOS are multiplied with the second, third, fourth, fifth, and sixth levels of the office selectors in the Midway office. As there are only a few districts in the first city it is not necessary to assign all of the levels of the selectors DOS for the outgoing trunks extending to the various districts and therefore the remaining levels may be used for trunking into the various offices in the sixth district, only five in number. Since the selectors DOS have access to trunk lines extending to the various offices in the sixth district and since such selectors are in the Midway office the district selecting digits can be skipped by the register senders in case the call is for a subscriber in the sixth district because the call already has been extended to a switch located in the sixth district.

The automatic subscriber's station designated A2 and the lineswitch LS2 in the South office are similar to the automatic subscriber's stations A and lineswitch LS in the Muncie office. Calls from subscriber A2 to the subscribers whose lines terminate in the South office extend by way of district selectors such as DS'' through office selectors such as OS'', thousands and hundred selectors such as TS'' and HS'' to connector switches such as C''.

The outgoing calls from the South office to subscribers' lines in the Muncie or Midway offices are extended by way of the trunk lines in the tenth level of the district selectors such as DS'' to the trunk relay groups such as TR'

in the Midway office. The incoming calls from the first city, such as the Muncie and the Midway offices, are extended over trunk lines which terminate in incoming district selectors, such as IDS, the banks of which are connected in multiple with the banks of the district selectors DS''. The tenth level of the incoming district selectors IDS, however, are not multiplied with the district selectors DS''.

In Fig. 2 the trunk relay group TR, comprising a plurality of relays, is shown in detail. Associated with the trunk relay group TR is a register sender selector RSS which is of the same mechanical construction as the well known rotary lineswitch in which the wipers have no normal position. The register sender selector RSS is individual to the trunk relay group TR and has access to a group of register senders one of which is shown in detail in Fig. 3. To the right of the trunk relay group and associated therewith there is shown an outgoing secondary lineswitch OLS which is mechanically the same as the register sender selector RSS and which has access to the trunk lines extending to the incoming district selectors such as IDS in the South office via the trunk repeaters such as REP. Repeaters and incoming district selectors of this type are well known in the art and as they form no part of the present invention they are only diagrammatically shown. In the lower right hand corner of Fig. 2 there is shown only that part of a tool recording operator's position which will enable the invention to be explained and understood. This equipment is individual to trunk relay group TR and consists of a pair of relays, a pair of lamps, a listening key LK for connecting the operator's head set to the trunk line in use, and a start key for restarting the register sender to transmit the remaining digits of the called number after the operator has been signalled and she has made a record of the call.

In Fig. 3 there is shown a register sender which is one of the group accessible to the register sender selector RSS Fig. 2. In the upper left hand corner of Fig. 3 there are shown the sequence switches S and S' which are used, respectively, to control the registration and retransmission of the impulses; in the lower right hand corner of Fig. 3 there is shown the sender switch SS which sends out the correct number of impulses for each digit; in the lower left hand corner there is shown the office register OR and the intermediate distributing frame IDF by means of which the office code may be readily changed; and in approximately the center of the figure there are shown the digit registers R1 to R4, inclusive, which are used to register the four subscriber's digits in a called telephone number.

Regarding the equipment involved in this figure, it may be said that the sequence switch

S' and the sending switch SS are of the well known rotary type of switch in which the wipers are moved in a forward direction only and are advanced upon the back stroke of the stepping magnet rather than upon the front stroke. The office register OR is an automatic switch of the well known Strowger type and its bank contacts are accordingly arranged in horizontal rows or levels. The sequence switch S together with the digit registers R1 to R4, inclusive, are of a simple type of switch having wipers which are advanced in a forward direction by a stepping magnet and which are restored to normal by the release magnet under the control of their respective off-normal contacts.

A detailed description of the operation of the apparatus shown will now be given. For this purpose it will be assumed that the subscriber at substation A in the Muncie office, desiring to make a call to substation A2 in the South office, removes his receiver. When this occurs, the individual lineswitch LS seizes an idle first selector such as DS in a well known manner. In order for the Muncie subscriber A to complete a connection to the South subscriber A2 it is necessary for subscriber A to dial the digit "0" before dialling the regular directory telephone number of subscriber A2. Responsive to dialling the digit "0" the first selector DS is operated in a well known manner to seize an idle outgoing trunk extending to the Midway office. Assuming that the trunk shown in Fig. 2 is the trunk over which the call is to be established, responsive to the seizure of this trunk a circuit is closed for line relay 31 of the trunk relay group TR as follows: ground by way of the lower winding of relay 31, resting contact of armature 41 and said armature, conductor 27 over the loop circuit via the seized repeater REP Fig. 1, conductor 25, armature 39 and its resting contact, to the upper winding of relay 31 and battery. Line relay 31 now energizes and at armature 34 closes a circuit for release relay 32 whereupon release relay 32 energizes and places ground upon release trunk conductor 43 at armature 36 and at armature 37 closes a circuit for switching relay 81 and stepping magnet 82 of the register sender selector RSS in series, and at armature 38 connects test wiper 89 to the junction of the said switching relay and stepping magnet.

The operation now depends upon whether the trunk terminating in the bank contacts upon which the wipers of the register sender selector are standing is busy or idle. Assuming first that the trunk is idle, switching relay 81 energizes immediately, seizing the trunk. Due to the high resistance of the switching relay the stepping magnet is not energized in series with said relay. Assuming now that the trunk upon which the wipers

of the register sender selector are standing is busy, switching relay 81 is short circuited by ground potential encountered on the busy test contact by test wiper 89 and does not energize. Stepping magnet 82, which interrupts its own circuit, is operated from this same ground potential through test wiper 89 and advances the wipers 87 to 90, inclusive, step by step in search of an idle trunk. Assuming that the trunk comprising conductors 91 to 94, inclusive, is the first one found to be idle, the wipers 87 to 90, inclusive, are rotated and stopped in engagement with the bank contacts in which the said conductors 91 to 94, inclusive, terminate, whereupon switching relay 81 energizes and grounds test wiper 89 at armature 85, thereby making the seized register sender busy immediately. As a further result of the energization of switching relay 81, it prepares the switching-through circuit at armature 86, at armature 83 prepares a circuit for signalling the toll recording operator; and at armature 84 closes the circuit for energizing relay 30 as follows: grounded armature 187 (Fig. 3), conductor 92, wiper 88, armature 84 and its working contact, and winding of relay 30 to battery. Relay 30, upon energizing, at armature 45 connects a bridge across trunk conductors 42 and 44 extending to the outgoing secondary lineswitch OLS. Responsive to the closure of this bridge line relay 51 of the outgoing secondary switch OLS energizes over the following circuit: ground at armature 61, conductor 44, normally closed springs controlled by armature 41, armature 45, normally closed springs controlled by armature 39, conductor 42, armature 57 and its resting contact, and winding of relay 51 to battery. Line relay 51, upon energizing, at armature 54 grounds the release trunk conductor 43; at armature 55 connects the test wiper 73 to the junction of the switching relay 52 and stepping magnet 53, and closes a circuit at armature 56 through the switching relay 52 and stepping magnet 53 in series.

The operation depends upon whether the trunk terminating in bank contacts upon which the wipers of the lineswitch are standing is busy or idle. Assuming first that the trunk is idle switching relay 52 energizes immediately seizing the trunk.

Assuming now that the trunk upon which the wipers of the lineswitch are standing is busy, switching relay 52 is short circuited by the ground potential encountered on the busy test contact by test wiper 73 and does not energize. Stepping magnet 53 which interrupts its own circuit at armature 62 is operated from this same ground potential through test wiper 73 and advances the wipers 72 to 74, inclusive, step by step in search of an idle trunk. When an idle trunk is reached, which trunk, it will be assumed, is the one comprising conductors 75 to 77,

inclusive, extending to the repeater REP and the incoming first selector IDS in the South exchange, there is no ground potential encountered upon the test contact thereof by test wiper 73 and switching relay 52, being no longer short circuited; energizes. Stepping magnet 53, however, does not energize at this time, on account of the high resistance of the switching relay 52. Upon energizing, switching relay 52 disconnects test wiper 73 from the junction of its own winding and that of the stepping magnet 53; at armature 58 grounds release trunk conductor 43; connects ground through armatures 56 and 60 to the conductor 76 thereby making the seized trunk immediately busy; and at armatures 57 and 61 disconnects the line conductors 42 and 44 from the winding of the line relay 51 and ground, and extends them by way of wipers 72 and 74, conductors 75 and 77, to the line relay in the repeater REP. The line relay in the repeater energizes and prepares the repeater circuit for repeating impulses through to the incoming selector IDS. The circuit operations of the repeater and the incoming selector IDS, being well understood and forming no part of the present invention, are being omitted and will be referred to only briefly hereinafter. Before line relay 51 deenergizes ground is fed from armature 79 in the repeater for maintaining the switching relay 52 in operated position.

Responsive to the grounding of conductor 93 by switching relay 81, (Fig. 3) relay 173 energizes and at armatures 184 and 186 opens the release circuits of the register sender, and at armature 185 prepares the locking circuits for relays 172, 200 and 225.

The apparatus in Figs. 2 and 3 is now ready to receive the impulses generated by the calling subscriber. The calling subscriber A will now dial the regular directory telephone number of the desired subscriber A2 in the South office.

When the calling subscriber manipulates his calling device in accordance with the first digit in the called number, the circuit of line relay 31 of the trunk circuit TR is opened a corresponding number of times. Upon each of the resulting deenergizations of line relay 31, it closes at armature 35 a circuit for the vertical magnet 151 of the office register OR Fig. 3 as follows: from ground by way of resting contact of armature 35 and said armature, armature 86, wiper 90, conductor 94, slow acting series relay 101 (Fig. 3), wiper 109 of sequence switch S, the vertical operating conductor 115, and vertical magnet 151 of the office register OR to battery. By the operation of the vertical magnet 151, the wipers 155 to 158, inclusive, of the office register OR are raised step by step and come to rest opposite the desired level of bank contacts. Relay 101 is energized in series with the vertical magnet, and being slow acting, maintains its

armature attracted throughout the series of impulses. Upon energizing, relay 101 closes at armature 103 a circuit for slow acting relay 102 which thereupon energizes and prepares at armature 104 a circuit for stepping magnet 105 of the sequence switch S.

At the end of the series of impulses transmitted to the vertical magnet of the office register OR, slow acting series relay 101 deenergizes and closes at armature 103 the circuit of the stepping magnet 105 of the sequence switch S, whereupon the stepping magnet 105 energizes and advances the wipers 108 and 109 into engagement with the second set of bank contacts. A moment later, slow acting relay 102, whose circuit is open at armature 103, deenergizes and opens the circuit of magnet 105 at armature 104.

The impulse distributing wiper 109 of the sequence switch S is now in engagement with the bank contact associated with the rotary magnet 152 of the office register OR. Accordingly, when the calling subscriber manipulates the calling device in accordance with the second digit in the desired number, the resulting series of impulses is transmitted over the circuit above traced to wiper 109 of the sequence switch S and thence by way of the second associated bank contact, and conductor 116 to rotary magnet 152. By the operation of the rotary magnet 152, wipers 155 to 158, inclusive, of the office register OR are rotated into engagement with the desired set of bank contacts in the level selected by the first digit, which contacts, it will be assumed, are the contacts indicated by reference numerals 214 to 217, inclusive.

At the end of this second series of impulses, the wipers 108 and 109 of the sequence switch S are advanced in the hereinbefore described manner, and wiper 108, upon coming into engagement with the third associated bank contact, connects ground to the interrupter 176 thereby starting the sending switch SS in the manner to be pointed out hereinafter. In addition, wiper 108 in its third position closes an energizing circuit for relay 225 which thereupon energizes and locks itself in energized position at armature 226. Relay 225 now maintains conductor 129 grounded so that the sender start circuit is not interrupted when wiper 108 moves to its seventh position.

When the first subscriber digit is dialed, the stepping magnet 161 of the first digit register R1 is operated over the circuit including the wiper 109 of the sequence switch S and conductor 121. Stepping magnet 161 advances the wiper 159 into engagement with the bank contact corresponding to the digit dialed. In the same way, responsive to the second, third, and fourth subscriber digits, the digit registers R2, R3, and R4, respectively, are operated over conductors 122, 123, and 124, respectively, and each advances its wiper into engagement with the bank con-

tact corresponding to the number of impulses received.

Returning now to the point at which the wiper 108 connected ground to the interrupter 176 to start the sender, the circuit for operating the stepping magnet 196 of the sending switch SS may be traced as follows: 5 grounded wiper 108, third bank contact accessible to wiper 108, multipled contacts connected jumper 127, terminal 125, conductor 129, multipled connected bank contacts of sequence switch S', wiper 110, conductor 130, interrupter 176, resting contact of armature 193 and said armature, and winding of stepping magnet 196 to battery. Upon the first energization of stepping magnet 196, the associated armature is attracted and moves the pawl into engagement with the next notch in the wiper driving ratchet wheel but does not 10 move the wipers 194 and 195. At armature 198 the stepping magnet 196 removes one of the ground connections from sending conductor 92 without effect at this time because the sending conductor 92 is grounded at armature 187 of the pickup relay 174.

Upon the subsequent deenergization of stepping magnet 196, the wipers 194 and 195 are advanced into engagement with the next set of bank contacts. When this occurs, wiper 195 engages a grounded contact, whereupon pickup relay 174 energizes and removes at armature 187 the ground from impulse conductor 92. At this time, however, ground is again applied at armature 198 so as not to 20 send out an impulse over conductor 92 on the first step of the sending switch SS. Relay 174 also places an auxiliary ground on conductor 93 at armature 188 so as to maintain the register sender busy until the sender has completed its operation in case the calling subscriber should hang up prematurely. As a further result of the energization of the pickup relay 174, it closes at armature 189 a circuit over conductor 118 for the stepping 25 magnet 111 of sequence switch S', whereupon the stepping magnet 111 energizes preparatory to advancing its associated wipers.

When ground is disconnected from the impulsive conductor 92 at armature 187, each 30 of the subsequent energizations of the stepping magnet 196 results in the transmission of an impulse over the impulse conductor 92. The wipers of the sending switch are advanced in the usual manner upon each subsequent deenergization of the stepping magnet 196. Now, referring to the office register OR it will be noted that the first wiper 155 of the office register OR is in engagement with the bank contact 214, which is cross-connected 35 on the intermediate distributing frame IDF by means of a jumper to the seventh impulse stop conductor 7. Accordingly, the first code digit to be transmitted is the code digit 7, and when 7 interruptions occur in the impulse conductor 92, the stop wiper 194 of the

sending switch is advanced into engagement with the bank contact in which the seventh impulse stop conductor 7 terminates, and stop relay 175 energizes over the following circuit: from ground by way of the stop conductor control wiper 113 of the sending control sequence switch S', the first associated bank contact, the first code digit stop conductor 131, wiper 155, bank contacts 214, the jumper on the intermediate distributing frame DF, the seventh impulse stop conductor 7, the corresponding contact in the bank of wiper 194, conductor 140, and stop relay 175 to battery. Upon the closure of this circuit, stop relay 175 energizes and grounds the impulse conductor 92 at armature 190 thereby terminating the transmission of impulses. Stop relay 175 also opens the circuit of the stepping magnet 111 of sequence switch S' and closes a locking circuit for itself at armature 192; and shifts at armature 193 the circuit of the stepping magnet 196 from the interrupter 176 to wiper 195 through the interrupter contacts 197.

As a result of opening the circuit of stepping magnet 111 of the sequence switch S' at armature 192, stepping magnet 111 de-energizes and advances its wipers 110, 113, and 114 into engagement with the second set of bank contacts; and as a result of shifting the circuit of the stepping magnet 196 of the sending switch SS at armature 193, stepping magnet 196 is operated through wiper 195 and interrupter contacts 197 to advance its wipers step by step until wiper 195 engages its normal position bank contact. With the wipers of the sending switch SS in their normal position the circuit of the pickup relay 174 is opened and said relay after an interval deenergizes.

In the trunk relay group TR Fig. 2, as a result of each of the seven interruptions of ground from the impulse conductor 92, relay 30 of the trunk relay group deenergizes a corresponding number of times thereby interrupting the loop circuit at armature 45 extending to the repeater REP. The repeater in a well known manner repeats the impulses over the trunk extending to the incoming district selector IDS and said incoming district selector is operated responsive to said interruptions to step the switch opposite the seventh level of bank contacts to which it has access. The incoming district selector IDS, after the cessation of impulses, automatically hunts for and finds an idle trunk in the seventh level extending to an office selector such as OS".

In the register sender, the slow acting pickup relay 174 falls back at the end of the 125 interval for which it is adjusted and opens the circuit of the slow acting stop relay 175 at armature 189. Stop relay 175, being also slow to release, falls back after an interval and again starts the sender. The interval re- 130

quired for relays 174 and 175 to fall back one after the other is made use of by the selector IDS to perform the change-over and trunk-hunting operations above described. As a further result of the deenergization of the slow acting pickup relay 174 it replaces ground on the impulse conductor 92.

At the end of the time for which it is adjusted, relay 175 deenergizes and at armature 193 it again connects stepping magnet 196 of the sender switch SS to the interrupter 176, thereby starting the sender for the transmission of the second and last code digit. Upon the first energization and deenergization of the stepping magnet 196 the circuit for pickup relay 174 is again closed over wiper 195. Pickup relay 174 accordingly energizes; again closes the circuit for stepping magnet 111 at armature 189; and 20 at armature 187 again removes one of the ground connections from impulse conductor 92. Accordingly, upon each of the following energizations of the stepping magnet 196 ground is removed from the impulse conductor 92 for controlling the operation of relay 30 in the trunk relay group TR as previously described.

At the end of the six interruptions produced over conductor 92 by stepping magnet 196, stepping magnet 196 deenergizes and again connects ground to impulse conductor 92 and again advances the wipers 194 and 195. Wiper 194, at this time engages the bank contact in which the sixth impulse stop conductor 6 terminates thereby closing a circuit for stop relay 175 as follows: from ground by way of stop conductor control wiper 113 of the sequence switch S', the second associated bank contact, the second code digit stop conductor 132, wiper 156, bank contacts 215, the jumper connected to the sixth impulse stop conductor 6, the associated contact in the bank of wiper 191 of switch SS, conductor 140, and winding of stop relay 175 to battery. Upon energizing, stop relay 175 again grounds the impulse conductor 92, again completes the locking circuit for itself, again opens the circuit of stepping magnet 111, and again completes the restoring circuit for the sending switch SS in the same manner as previously described.

Returning now to the point at which the circuit of the stepping magnet 111 of the sequence switch S' was opened at the end of the second code digit, stepping magnet deenergizes and advances the wipers 110, 113 and 114 out of engagement with the second set of bank contacts and into engagement with the third set, whereupon wiper 113 grounds the third code digit stop conductor 133. Since only two code digits are needed to trunk the call to the desired office in this case, the third and fourth bank contacts 216 and 217 of the office register OR are cross-connected by means of a number of jumpers

to the skip conductor 119. Accordingly, when the third code digit stop conductor 133 is grounded by wiper 113, a circuit is closed through wiper 157, bank contact 216, the jumper on the IDF to conductor 119, and from there to the interrupter contact 112 of the stepping magnet 111 of the sequence switch S'. The stepping magnet 111 thereupon energizes and interrupts its own circuit at contact 112 whereupon it deenergizes and advances the wipers 110, 113 and 114 another step. Wiper 113 at this time extends ground over the fourth code stop conductor 134 to the fourth office register wiper 158 and thence by way of bank contact 217 over the previously traced circuit to stepping magnet 111. Accordingly, the wipers 113 and 114 are automatically advanced another step and wiper 113 places ground on the first subscriber digit stop conductor 141.

The starting of the sender SS is now dependent upon whether the calling subscriber has dialed the second subscriber digit or not. Assuming that the calling subscriber has dialed the second subscriber's digit then the register switch R2 is operated and ground is connected by way of off-normal spring 178, conductor 135, wiper 110, conductor 130 to the interrupter 176 for again starting the sender to transmit the subscriber digits.

When the sender is started for the third time it transmits the first subscriber's digit which is registered on the digit register R1. This digit is terminated in the hereinbefore described manner when wiper 194 of the sending switch SS arrives upon the impulse stop conductor upon which wiper 159 of the digit register R1 is standing. The wipers of the sending switch are rotated back to their initial starting position and the transmission of the second subscriber's digit starts providing the third register R3 has been operated by the calling subscriber thereby causing the register R3 to apply ground to conductor 136 for again starting the sender switch SS.

After transmission of the first subscriber's digit, the wipers of the sequence switch S' are advanced in the same manner as previously described and wiper 113 connects ground to the second subscriber's digit stop conductor 142 in order to terminate the second subscriber's digit, as determined by the setting of the digit register R2. In the same way, the wipers 110, 113, and 114 of the sequence switch S' are advanced at the end of the second subscriber's digit, and ground is extended over the third subscriber's digit stop conductor 143 to the wiper of the third digit register R3. The starting of the sender is now dependent upon whether the calling subscriber has dialed the fourth and last subscriber's digit. Assuming that the calling subscriber has operated the digit register R4, ground is connected by way of off-normal springs 130

179 to conductor 137 to again start the sender switch SS in the same manner as previously described. The third subscriber's digit as determined by the setting of the digit register R3 is now sent and after termination of impulse transmission the sequence switch S' moves one step to its next position and at wiper 113 the sequence switch S' grounds the fourth subscriber digit stop conductor 144. The sending switch SS is again restored to its normal position and the pickup relay 174 and stop relay 175 are again deenergized preparatory to sending the fourth and last subscriber digit.

15 It will be remembered that the sequence switch S advances one step after each series of impulses and when the calling subscriber has dialed the last digit of the called number the sequence switch S will be advanced to 20 its seventh position whereupon a circuit is closed for energizing relay 63 (Fig. 2) as follows: ground by way of wiper 108, seventh bank contact accessible to wiper 108, jumper 128, terminal 126, resting contact of armature 25 223 and said armature, winding of relay 171, conductor 91, bank contact accessible to wiper 87 and said wiper, armature 83 and its working contact, conductor 29, and winding of relay 63 to battery. Relay 171, being marginal, does 30 not energize in this circuit but relay 63, upon energizing, at armature 65 closes a circuit for lighting the call lamp 69 at the toll recording operator's position. The toll recording operator operates the listening key LK there- 35 by connecting her head set directly across the trunk conductors 25 and 27 via the conductors 26 and 28. After receiving the desired information from the calling subscriber the toll recording operator makes the usual toll 40 ticket and momentarily presses the start key whereupon relay 64 energizes. Relay 64, upon energizing, at armature 66 completes a locking circuit for itself over the grounded conductor 29; at armature 67 opens the cir- 45 cuit of the call lamp 69; and at armature 68 closes a circuit for lighting the sending lamp 70 which lamp remains lighted until the register sender and register sender selector are released after the final digit has been sent.

50 When the start key is released, relay 171 in the register sender energizes due to the combined current flow through relays 63 and 64. Relay 171, upon energizing, at armature 180 closes an energizing circuit for relay 172 55 whereupon the latter relay energizes and at armature 181 completes a locking circuit for itself. Relay 172 at armature 182 connects ground to conductor 129 which however is without result at this time; and at armature 60 183 connects ground to conductor 138 in order to start the sending switch SS to send the fourth and last subscriber's digit. The circuit for starting the sender may be traced as follows: from ground by way of armature 65 183, conductor 138, wiper 110, conductor 130, interrupter 176, resting contact of 193 and said armature, and winding of stepping magnet 196 of the sending switch SS to battery. The fourth and last subscriber's digit is sent in the same manner as previously described 70 and after the termination of the impulse transmission the sending switch SS returns to its normal position and the pickup relay 174 and stop relay 175 deenergize in the manner previously described. The stepping magnet 111 of the sequence switch S' is again operated and when the stepping magnet 111 deenergizes and advances the wipers of the sequence switch S' a circuit is closed for energizing the switching through relay 33 as 80 follows: from grounded wiper 113 by way of conductor 94, bank contact of director selector, wiper 90, armature 86, armature 35 and its working contact, and winding of switching through relay 33 to battery. 85 Switching relay 33, upon energizing, closes a locking circuit for itself at armature 40 by way of grounded release trunk conductor 43; and at armatures 39 and 41 disconnects the conductors 25 and 27 from the windings 90 of the line relay 31 and connects them instead to conductors 42 and 44 extending to the outgoing secondary line switch OLS, at the same time disconnecting the bridge across the conductors 42 and 44 which is closed at armature 45 of relay 30. The established connection is now under the direct control of the calling line, and the established connection is held by the repeater REP in the usual manner.

95 As a result of the line relay 31 of the trunk relay group TR being cut off, it deenergizes and opens the circuit of the release relay 32 at armature 34. In response to this, relay 32 deenergizes after a slight interval and removes ground from release trunk conductor 43 at armature 36, leaving the release trunk conductor grounded at armature 58.

100 As a further result of the deenergization of the release relay 32, it opens at armature 37 the circuit of switching relay 81 of the register sender selector RSS whereupon the switching relay 81 deenergizes.

105 In the register sender, the release relay 173 now deenergizes and at armature 184 110 connects ground to conductor 117 which is connected to the bank contacts accessible to wiper 114 of the sequence switch S', thereby closing a circuit through wiper 114 for the stepping magnet 111, whereupon stepping 115 magnet 111 energizes and interrupts its own circuit at contact 112, thereby deenergizing and advances the wipers 110, 113 and 114 to their normal positions. As a further result of the deenergization of relay 173, ground 120 is placed on the release trunk conductor 220 at armature 186. Responsive to this, a circuit is closed through the off-normal contacts to each of the release magnets of the digit registers R1 to R4, inclusive, where- 125 130

upon the digit registers are restored to their normal positions in the usual manner. For example, release magnet 160 of the digit register R1 energizes through off-normal contacts 199 and restores the wiper 159 to normal, whereupon the off-normal contacts 199 are opened thereby interrupting the circuit to release magnet 160. In the same way the release magnet 150 of the office register OR is operated to restore the switch to normal position over a circuit including the off-normal springs 153 and conductor 220. The sequence switch S is restored to normal position by the operation of release magnet 106 over a circuit including the off-normal springs 107. As a further result of the deenergization of relay 173 the locking circuits of relays 172 and 225 are opened and said relays release.

20 When the switching relay 81 of the register sender selector deenergizes said relay at armature 83 opens the circuit of relays 63, 64, and 171 thereby permitting said relays to return to normal. At armature 68 relay 34 opens the circuit of the sending lamp 70 thereby informing the toll recording operator that the last subscriber's digit has been sent by the register sender and that the register sender has been cut off. The toll recording operator may now listen in over the conductors 26 and 28 to determine whether or not the calling subscriber has completed a talking connection with the desired called subscriber.

35 After the sequence switch S', the sequence switch S, the digit registers R1 to R4, inclusive, and the office register have returned to their normal positions the register sender may again be seized for handling other calls.

40 Regarding the established connection, it may be pointed out that the usual chain of automatic switches in the called office is operated responsive to the four subscriber's digits of the number to complete the connection, whereupon the conversation may be carried on in any desired manner.

When the conversation is terminated, the subscriber at substation A replaces his receiver, whereupon ground is removed from 50 release conductor 76 by the deenergization of the line and release relays in the repeater in the usual manner, whereupon the switching relay 52 of the outgoing secondary line switch OLS deenergizes. At armature 58 switching relay 52 removes ground from release trunk conductor 43 thereby permitting switching through relay 33 of the trunk relay group TR to deenergize. The trunk relay group TR and the outgoing secondary lineswitch OLS are now in normal position and may be used in establishing other calls. The repeater REP, the incoming district selector IDS and the remaining switches in 55 the connection release in the well known

manner and may be used in handling other calls.

Having described the detail circuit operations of the trunk relay group TR and the register sender RS in a toll connection from the Muncie office to the South office, a description of the circuit operations of the trunk relay group TR' and the register sender RS' will be now given in a toll connection from the South office to the Muncie 70 office. In order not to complicate and increase the drawings it will be assumed that the trunk relay group TR Fig. 2, the register sender selector RSS Fig. 2, and the register sender RS, Fig. 3 are selectable from the district selector DS'' in the South office via the repeater (shown in Fig. 1). In addition, the trunk relay group will have direct access to the office selector DOS in the Midway office 75 instead of to the outgoing secondary switch QLS shown in Fig. 2. With this arrangement, trunk conductors 42 and 44 are connected to the windings of the line relay in the office selector DOS in the usual manner, and the release trunk conductor 43 is connected to the incoming release trunk conductor of the office selector, the office selector being a standard Strowger vertical and rotary switch. With this trunking arrangement, the register selector RS, Fig. 3 may 80 be used without any circuit changes for completing calls to subscribers such as subscribers A and A' in the Muncie and Midway offices, respectively.

With this trunking layout in mind it will 100 now be assumed that subscriber A2 in the South office removes his receiver to make a call. After his individual lineswitch LS2 has seized the district selector DS'' in the usual manner, the calling subscriber will dial the digit "0" before dialling the regular directory telephone number of subscriber A in the Muncie office. When the district selector DS'' seizes the trunk extending to the repeater REP in the South office the repeater 105 closes the usual bridge across the trunk conductors extending to the trunk relay group TR' shown in Fig. 1 to cause the operation of the line relay in the trunk relay group. Referring now to Fig. 2 and assuming that the trunk relay group TR is accessible from the South office, a circuit may be traced over conductors 25 and 27 and armatures 39 and 41 for energizing line relay 31 of the trunk relay group TR. The operation of the trunk relay group TR and the register sender selector is now the same as previously described with the result that when the register sender selector seizes an idle register sender such as shown in Fig. 3 the bridge relay 30 energizes 115 to close the bridge across the conductors 42 and 44 which now extend to the office selector DOS thereby causing the line relay in said switch to energize.

Responsive to the seizure of the register 120

sender RS by the register sender selector RSS the release relay 173 energizes and opens the release circuits of the various switches in the sender in the same manner as previously described. The calling subscriber A2 in the South office may now dial the regular directory telephone number of the called subscriber A in the Muncie office, the district and office selecting digits in this instance being 6 and 6, respectively, and the subscriber's digits being 3222. Responsive to dialing the number 663222 the register sender Fig. 3 is operated in the same manner as previously described, the wipers 155 to 158, inclusive, of the office register OR being set on the bank contacts 210 to 213, respectively, and the subscribers' digit registers R1 to R4, inclusive, being set on the third, second, second, and second bank contacts, respectively. After the calling subscriber has dialed the district selecting digit 6 and the office selecting digit 6 the sequence switch S is stepped to its third position and a circuit is closed by wiper 108 for starting the sender SS in the same manner as previously described. Due to the cross-connections at the IDF the register sender sends only the office selecting digit 6. This circuit may be traced from grounded wiper 113, conductor 131, wiper 155, bank contact 210 which is cross connected to the number 6 subscriber digit, stop conductor, wiper 194, conductor 140 and winding of stop relay 175 to battery. The pickup and stop relays operate in the same manner as previously described and cause the stepping magnet 111 of the sequence switch S' to take one step whereupon the conductor 132 extending to wiper 156 of the office register OR is grounded. Wiper 156 being in engagement with bank contact 211 and such bank contact being cross-connected to the skip conductor 119, the sequence switch S' is automatically stepped one step from its second to its third position. Due to the cross-connections from the bank contacts 212 and 213 to the skip conductor 119 the sequence switch S' is stepped from its third and fourth positions to its fifth position or the first subscriber digit position. The sender now sends out the subscriber's digits in the same manner as previously described, stopping; however, after the third subscriber digit to signal the toll recording operator in the same manner as previously described. After receiving the desired information the toll recording operator again presses the start key to allow the sender to transmit the final or last subscriber's digit. After the sender has transmitted the last subscriber's digit the switching relay 33 of the trunk relay group TR is energized over the circuit previously described with the result that the register sender selector and the register sender are cut off and are available for other calls. Relay 33

at armature 40 completes a circuit for locking itself to grounded release trunk conductor 43. In addition, relay 33 at armature 39 and 41 connects the trunk conductors 25 and 27 to the trunk conductor 42 and 44 which extend to the office selector DOS. The established connection is now under direct control of the calling subscriber. The toll recording operator by operating her listening key LK can at any time listen in on the trunk to determine whether or not the calling subscriber A2 should be charged for the call.

Regarding the established connection, it may be pointed out that since the combined district and office selector DOS is located in the 6th district and has direct access to trunks outgoing to the 6th office in the 6th district it is unnecessary for the register sender to transmit the district selecting digit and therefore such digit is skipped. The usual train of automatic switches in the called office is operated responsive to the four subscribers' digits of the number to complete the connection, whereupon the conversation may be carried on in any desired manner.

When the conversation is finished, the subscriber at substation A2 replaces his receiver, whereupon ground is removed from the release trunk conductor extending from the office selector DOS to conductor 43 over which the switching through relay 33 has been maintained in energized position. Switching through relay 33 deenergizes and returns the trunk relay group to normal condition. The release of the automatic switches in the established connection is now the same as previously described.

Having described a toll connection from the South office to the Muncie office, a description will now be given of a call from the South office to the Midway office describing how the register sender RS Fig. 3 discriminates between a call from the South office to the Muncie office and a call from the South office to the Midway office. In calls from the South office to the Midway office the register sender transmits the whole of the subscriber's number without signalling the toll recording operator. It will be remembered that calls from either city to the Midway office are not assessed a toll charge and therefore it is not necessary in calls from the South office to the Midway office to cause the register sender to signal the toll recording operator. A discriminating relay 200 in the register sender RS is operated on such calls to open the circuit for signalling the toll recording operator and said relay also closes a circuit for causing the sender to complete the sending operation.

When subscriber A2 removes his receiver in order to make a call to subscriber A' in the Midway office, the lineswitch LS2 again seizes a district selector switch such as DS''. The calling subscriber now dials the digit "0" be-

fore dialling the regular directory telephone number of the called subscriber A' in the Midway office. The trunk relay group TR' is again seized in the same manner as previously described. The register sender selector again seizes an idle register sender after which the calling subscriber dials the district selecting digit 6 and the office selecting digit 5. Responsive to dialling the district and office selecting digits 6 and 5 the wipers 155 to 158, inclusive, of the office register OR come to rest in engagement with bank contacts 206 to 209, respectively.

Responsive to dialling the subscriber's digits the registers R1 to R4 are set in the same manner as previously described. When the sequence switch S arrives in third position the sending switch SS is started to transmit the first office code.

After wiper 108 of the sequence switch S arrives in its third position a circuit is closed for starting the sending switch SS in the same manner as previously described. Due to the cross-connections at the IDF the sending switch SS and register sender transmit 5 impulses for the first office code. The sequence switch S' is now stepped to its second position whereupon a circuit is closed for energizing discriminating relay 200 as follows: from ground by way of wiper 113 in its second position, conductor 132, wiper 156, bank contact 207, terminal 207', jumper on IDF, terminal 203, conductor 201, normally-closed springs controlled by armature 220, and winding of relay 200 to battery. Upon energizing, relay 200 at armature 220 opens its original energizing circuit and closes a locking circuit for itself over the conductor extending from grounded armature 185. At armature 221, relay 200 connects the grounded conductor 201 to conductor 202 and thence by way of terminal 204 and jumper on the IDF to skip conductor 119. At armature 224, relay 200 prepares a circuit for connecting ground to the sender start conductor 138 which terminates in the bank of the sequence switch S'. After transmitting the five impulses constituting the office code the sequence switch S' is automatically stepped to its fifth position due to the cross-connections of bank contacts 207, 208, and 209 to the skip conductor 119. The register sender and the sending switch now operate and send out all of the subscriber's digits which have been registered on the subscriber digit registers R1 to R4, inclusive.

It will be noted that due to the operation of relay 200 the circuit for signalling the toll recording operator is opened at armature 223 while at armature 224 the sender is automatically started to send the last subscriber digit provided, at such time, the calling subscriber has operated the register R4. After the register sender has transmitted the last digit the switching through relay 33 is operated and switches the connection over

under control of the calling subscriber. The register sender selector and the register sender are released in the same manner as previously described and may be used for handling other calls.

The office selector DOS is operated by the impulses transmitted by the sender opposite the fifth level of bank contacts. Referring to Fig. 1 it will be seen that the fifth level is in multiple with the fifth level of the second selector OS' and that such trunks have access to thousand selectors such as TS'. The office selector DOS automatically rotates for an idle trunk in the fifth level and seizes the first idle one which we will assume is the trunk extending to the thousand selector TS'. The thousand selector TS', the hundred selector HS' and the connector C' are now operated in the well known manner responsive to the digits transmitted by the sender to complete the connection to the called line.

When the conversation is terminated the subscriber at substation A2 will replace his receiver, whereupon ground is removed from the release trunk conductor 43 thereby enabling switching through relay 33 to release. The automatic switches in the established connection will now release and may be used for establishing other calls.

Referring to the trunking arrangement shown in the Midway office in Fig. 1 it will be seen that the outgoing trunks to the South office are seizable over two paths, one of the paths being accessible over the trunk lines extending from the district selector DS', for the purpose of enabling the Midway subscribers to call into the South office without being charged for such calls. The other path is selectable by way of the trunk relay group TR and the outgoing secondary line switch OLS in order to enable the toll recording operator to charge the call to the calling subscriber. In this manner a certain group of subscribers in the same automatic district are not charged for calls going to the second automatic district although such calling subscribers dial the same numbers and use a common group of trunks.

One order of automatic switches in the sixth district has been eliminated due to the ability of the register sender to skip a district selecting digit, thereby using the office selecting selector DOS as a combined district and office selecting selector. Referring to Fig. 1 it will be seen that the office selector DOS has access to trunks extending to the 7, 8, and 9th districts and to trunks extending to offices in the 6th district. This is possible because the office selectors are located in the 6th district and because of the limited number districts and the limited number of offices in the sixth district.

Suitable cross-connecting facilities comprising terminals and jumpers have been provided associated with the sequence switch S,

Fig. 3, in order to change the position in which the sequence switch S starts the sending switch SS. For example, assume that it is desired to start the sender only after the calling subscriber has finished dialling the complete telephone number of the desired called subscriber and after the toll recording operator has pressed her start key. Under this condition the jumper 127 would be cut and a circuit for starting the sending switch SS would be completed only after the relay 172 is energized responsive to operation of the start key.

From the foregoing it may be seen that the duties of a toll recording operator in such a system have been greatly reduced because all that is necessary for her to do is to make out the usual toll tickets, operate the start keys, and listen in to determine whether the calls have been completed before charging the calling subscribers.

Having described the invention, its utility and operation, what is considered new and is desired to have protected by Letters Patent will be set forth in the appended claims.

What is claimed is:

1. In a telephone system, a register sender for storing and transmitting a plurality of series of impulses corresponding to the digits in a called telephone number, and means in said sender for transmitting only a portion of the stored digits of a called telephone number and thereafter signalling a toll recording operator.

2. In a telephone system, a register sender for storing and transmitting a plurality of series of impulses corresponding to the digits in a called telephone number, means in said sender for transmitting only a portion of the stored digits of a called telephone number and thereafter signalling a toll recording operator, and manual control means controlled by the operator for restarting said sender to transmit the remaining stored digit or digits in the called telephone number.

3. In a telephone system, a register sender for storing and transmitting a plurality of series of impulses corresponding to the digits in a called telephone number, means in said sender for stopping the transmission of impulses and for signalling a toll recording operator after a predetermined number of digits in the called telephone number has been transmitted, and manual control means controlled by the operator for restarting said sender to transmit the remaining stored digit or digits in the called telephone number.

4. In a telephone system, a first telephone district and a second telephone district, a group of trunk lines for use in establishing connections from subscribers in said first district to subscribers in said second district, two groups of subscribers' lines in said first district, a called subscriber's line terminating in said second district, means responsive to

a calling subscriber in either of said groups dialling the telephone number of said called subscriber's line for establishing a connection over one of said trunk lines to the called subscriber's line, and means for causing only the calls from subscribers in the second group to said called line to be intercepted by a toll recording operator before the connection is completed.

5. In a telephone system, a first telephone district and a second telephone district, a group of trunk lines for use in establishing connections from subscribers in said first telephone district to subscribers in said second district, two groups of subscribers' lines in said first district having access to said group of trunk lines over different paths, means whereby the subscribers in the first group can complete connections to called subscribers' lines in the second district over said trunk lines without being charged for such connections, and means whereby the subscribers in the other group can complete connections to called subscribers' lines in the second district over said trunk lines only after such calls have been intercepted by a toll recording operator for the purpose of charging such calls.

6. In a telephone system, two groups of subscribers' lines, two classes of subscribers' lines in said first group, a group of trunk lines common to both of said classes, means for establishing connections from the first and second classes of subscribers' lines to said second group of subscribers' lines over said trunk lines, said means operated responsive to the calling subscribers dialling the same predetermined digit and the regular directory telephone number of the called line, and means for intercepting only the calls originating from the second class subscribers' lines.

7. In a telephone system, two groups of subscribers' lines, two classes of subscribers' lines in said first group, a group of trunk lines common to both of said classes, means for establishing connections from the first and second classes of subscribers' lines to said second group of subscribers' lines over said trunk lines, said means operated responsive to the calling subscribers dialling the same predetermined digit and the regular directory telephone number of the called line, means for intercepting only the calls originating from the second class subscribers' lines, and manual controlled means for completing the intercepted calls.

8. In a telephone system, a register sender for storing and transmitting a plurality of series of impulses corresponding to the digits in a called telephone number, a toll recording operator's position and a signal thereat, and discriminating means in said sender for stopping the transmission of impulses before all the digits have been transmitted and for oper-

ating said signal, said means being operative dependent upon the destination of the call set up on the sender.

9. In a telephone system, a register sender for storing and transmitting a plurality of series of impulses corresponding to the digits in a called telephone number, a toll recording operator's position and a signal thereat, means including an impulse distributor switch in said sender for starting the transmission of digit impulses after a predetermined number of digits have been dialled by the calling subscriber, for stopping the transmission of impulse digits by said sender after a predetermined number of digits have been transmitted, and for closing a circuit for operating said signal after the calling subscriber has dialled a predetermined number of digits, and means comprising terminals and cross-connections adapted to be variably connected to the banks of said switch for variably changing the starting, stopping, and signalling positions of said switch.

10. In a telephone system, a register sender for storing and transmitting a plurality of series of impulses corresponding to the digits in a called telephone number, a toll recording operator's position and a signal thereat, means operated responsive to a calling subscriber dialling a predetermined number of the digits of a called subscriber's telephone number for starting the sender to transmit impulses, means operated after the calling subscriber has finished dialling all the digits in the called subscriber's number, for operating said signal, and means comprising variable cross connections whereby the sender is not started transmitting until after said signal has been operated.

40 11. In a telephone system, a trunk line having incoming and outgoing sections, a register sender connected to said trunk line at the junction of said sections for storing a plurality of series of impulses corresponding to the digits in a called telephone number received over the incoming section of said trunk line and for transmitting a plurality of series of impulses corresponding to the stored digits over the outgoing section of said trunk line, means in said sender for stopping the transmission before all of the stored digits are transmitted, and means exclusive of control over the outgoing section for restarting said sender to transmit the remaining stored digits.

55 12. In a telephone system, a first called subscriber's line, a second called subscriber's line, a trunk line having incoming and outgoing sections, a register sender connected to said trunk line at the junction of said sections for storing a plurality of series of impulses corresponding to the digits in a called telephone number received over the incoming section of said trunk line and for transmitting a plurality of series of impulses corresponding

to the stored digits over the outgoing section of said trunk line, an operator's position and a signal thereat, means in said sender for stopping the transmission before all of the stored digits are transmitted and thereafter operating said signal in case said first line is called, and means exclusive of control over the outgoing section for restarting said sender to transmit the remaining stored digits, said sender transmitting all of the stored digits without stopping and signalling the operator in case the second line is called.

70 13. In a telephone system, two telephone districts, a main and a branch exchange in the second district, a trunk line having incoming and outgoing sections in said branch exchange, said incoming section extending to an exchange in the first district, a register sender in the branch exchange, two branches of said trunk line terminating at the junction of said incoming and outgoing sections, one of said branches terminating in an operator's position and the other branch connected with said sender, means in said sender responsive to a calling subscriber in the exchange in the first district dialling the telephone number of a desired subscriber's line in the second district over the incoming section of said trunk line for storing the digits of the called number, means in said sender for transmitting over the outgoing section of said trunk line a plurality of series of impulses corresponding to the digits stored, means in said sender for stopping the transmission of impulses before all of the stored digits have been transmitted and for thereafter signalling the operator over said first branch in case a subscriber's line in the main exchange is called, and means in said sender controlled over said first branch for restarting said sender to transmit the remaining stored digits in order to complete the connection, said sender transmitting all of the stored digits without stopping and signalling the operator in case a subscriber's line in the branch exchange is called.

80 14. In a telephone system, a register sender for storing and transmitting a plurality of series of impulses corresponding to the office digits and subscriber's digits in a called telephone number, means in said sender for starting the transmission of the stored digit impulses, means in said sender for stopping the transmission of the stored digits after all of the office digits and a predetermined number of the subscriber's digits have been transmitted, and directively controlled means for restarting said sender to transmit the remaining stored subscriber's digits.

85 15. In a telephone system, a register sender for storing and transmitting a plurality of series of impulses corresponding to the office digits and subscriber's digits in a called telephone number, discriminating means in said sender being operative dependent upon the

destination of the call set up on the sender, and means controlled by said discriminating means for stopping the transmission of impulses after all of the office digits and a predetermined number of the subscriber's digits have been transmitted.

16. In a telephone system, a register sender for storing and transmitting a plurality of series of impulses corresponding to the office digits and subscriber's digits in a called telephone number, means in said sender normally arranged to stop the transmission of impulses after all the office digits and a predetermined number of subscriber's digits have been transmitted, a toll recording operator's position, a signal thereat, means responsive to the operation of said last means for operating said signal, a start key at said position, and a relay in said sender operated responsive to the operation of said key for restarting said sender to transmit the remaining subscriber's digit or digits.

17. In a telephone system, a register sender for storing and transmitting a plurality of series of impulses corresponding to the office digits and subscriber's digits in a called telephone number, a toll recording operator's position and a signal thereat, means in said sender normally arranged for stopping the transmission of impulses after all the office digits and a predetermined number of subscriber's digits have been transmitted and for operating said signal, means for thereafter restarting said sender to transmit the remaining subscriber's digits, and a relay in said sender operated dependent on the office designation corresponding to the office digits stored for disabling said normally arranged means whereby said sender completes the transmission of the stored office and subscriber's digits without stopping to signal the toll recording operator.

18. In a telephone exchange system, two exchanges, automatic switching apparatus in each exchange operable under the direct control of calling subscribers to complete connections local to the exchange in which they originate, an inter-exchange trunk line, a register sender, and means only responsive to the seizure of said trunk line in making an inter-exchange call for seizing said register sender, said register sender thereafter controlling all the automatic switching apparatus in the called exchange.

19. In a telephone exchange system, two exchanges, automatic switching apparatus in each exchange operable under the direct control of calling subscribers to complete connections local to the exchange in which they originate, means including register senders for controlling the automatic switching apparatus in the called exchange when inter-exchange calls are made, a toll recording operator's position and a signal thereat, and means controlled by any one of said register

senders for operating said signal for the purpose of charging such calls.

20. In a telephone exchange system, two exchanges, automatic switching apparatus in each exchange operable under the direct control of calling subscribers to complete connections local to the exchange in which they originate, means including register senders for controlling the automatic switching apparatus in the called exchange when inter-exchange calls are made, a toll recording operator's position and a signal thereat, means controlled by any one of said register senders for partially operating a portion of said automatic switching apparatus to only partially complete the connection to a called line and for thereafter operating said signal, and means controlled by the operator for causing said register sender to complete the operation of said portion of the automatic switching apparatus to complete the partially completed connection.

21. In a telephone exchange system, two telephone districts each containing a number of exchanges, automatic switches in each district operable directly over the calling subscriber's loop to complete local and inter-exchange connections local to the district in which the calls originate, register senders, means only responsive to inter-district calls for seizing said register senders, means in each register sender for storing a plurality of series of impulses corresponding to digits in the called telephone number, and means in each register sender for transmitting a plurality of series of impulses corresponding to the stored digits for operating said switches to complete inter-district connections.

22. In a telephone exchange system, two telephone districts, automatic switches in each district operable directly over the calling subscriber's loop to complete connections local to the district in which the calls originate, a register sender, means only responsive to inter-district calls for seizing said sender, means in said sender for storing a plurality of series of impulses corresponding to the digits in the called telephone number, means in said sender for transmitting a plurality of series of impulses corresponding to the stored digits for operating said switches to complete inter-district connections, a toll recording operator's position and a signal thereat, and means in said sender for stopping the transmission of the stored digits after a predetermined number of stored digits have been transmitted and for thereafter operating said signal.

23. In a telephone exchange system, two telephone districts, automatic switches in each district operable directly over the calling subscriber's loop to complete connections local to the district in which the calls originate, a register sender, means only respon-

sive to inter-district calls for seizing said sender, means in said sender for storing a plurality of series of impulses corresponding to the digits in the called telephone number, 5 means in said sender for transmitting a plurality of series of impulses corresponding to the stored digits for operating said switches to complete inter-district connections, a toll recording operator's position and a signal 10 thereof, means in said sender for stopping the transmission of the stored digits after a predetermined number of stored digits have been transmitted and for thereafter operating said signal, and means for restarting 15 said sender to transmit the remaining stored digits.

24. In a telephone system, a trunk line, automatic switches, a register sender for controlling said switches over said trunk line 20 to establish a connection, means for stopping the control of said sender over said switches before the connection is completed, and means exclusive of control over said trunk line for restarting said sender to cause 25 said switches to complete the connection.

25. In a telephone system, a trunk line, automatic switches, a register sender for controlling said switches over said trunk line to establish a connection, means for stopping the control of said sender over said switches before the connection is completed, a toll recording operator's position and a signal 30 thereof, means for operating said signal before the connection is completed for the purpose of charging such calls, and means controlled by the operator after the call has been charged for restarting said sender to cause said switches to complete the connection.

40 26. In a telephone exchange system, two exchanges, an inter-exchange trunk line connecting said exchanges, automatic switches in the second exchange, a register sender in the first exchange for controlling said switches over said trunk line to establish a connection, means for stopping the control of said sender over said switches before the connection is completed, a toll recording operator's position in the first exchange, and 45 means controlled by the operator at said position for restarting said sender to cause said switches to complete the connection.

55 27. In a telephone exchange system, a first exchange, an intermediate exchange, and a third exchange, automatic switches in said third exchange, an inter-exchange trunk line connecting the third and intermediate exchanges, a register sender in the intermediate exchange for controlling said switches over said trunk line on calls originating from said first exchange to complete a connection to a subscriber's line in the third exchange, means for stopping the control of said sender over said switches after a pre-determined number 60 of said switches have been operated and be-

fore the connection is completed, and means exclusive of control over said trunk line for restarting said sender to cause the remaining switch or switches to be operated to complete the connection.

70 28. In a telephone system, two exchanges, an inter-exchange trunk line connecting said exchanges, automatic switching mechanism in said second exchange, a toll operator's position, a signal thereof, a register sender, means controlled by said register sender over said trunk line for partially operating said mechanism to partially extend a connection to a called line, means for operating said signal, and means for controlling said register sender from said operator's position to cause said mechanism to complete its operation to complete the connection to the called line.

75 29. In a telephone system, two exchanges, automatic switching apparatus in each exchange, means for operating all of the required switching apparatus directly over the calling subscriber's loop when the connection to be set up is local to the exchange in which it originated, a register sender, means responsive only to an inter-exchange call for seizing said register sender, and means in said register sender for storing those digits of the called number which determine the 80 setting of the automatic switching apparatus in the called exchange and for retransmitting the stored digits to operate said automatic switching apparatus to complete the connection.

90 30. In a telephone system, a first exchange and a second exchange, automatic switching apparatus in each exchange operable under the direct control of calling subscribers to complete connections local to the exchange in which they originate, a tandem exchange, automatic switching apparatus and a register sender in said tandem exchange, means for seizing said register sender responsive to part of the digits in a called number on a 95 call from said first to said second exchange, and means in said register sender for storing the remaining digits of the called number and for retransmitting the stored digits to operate the automatic switching apparatus in the tandem and in the second exchange to complete the connection.

100 In witness whereof, I hereunto subscribe my name this 7th day of September, 1927.

CLARENCE E. LOMAX.

105 In witness whereof, I hereunto subscribe my name this 7th day of September, 1927.

LEONARD L. RUGGLES.
